KNIT FABRIC AND GARMENT
CONSTRUCTION

Hans Boepple, Valley Cottage, N. Y.

Application March 16, 1939, Serial No. 262,170

2 Claims. (Cl. 66—169)

This invention relates to a knitted fabric construction and to garments made therefrom as well as to the method of knitting the same.

One of the principal objects of the invention is to knit a fabric construction from non-elastic and substantially non-stretchable lengths of woven fabric which, when made up into garments, will have sufficient elasticity to make it conform to the figure of the wearer.

Another object is to provide a garment made from narrow woven fabric in which the stitches are spaced comparatively widely apart to form substantially loose chain-like knots which become tightened when the garment or fabric is subjected to tension but which will resume their original condition when the tension is released.

Another object is to provide a knitted fabric of open work design and garments made therefrom which are produced from lengths of non-elastic woven ribbon.

Still a further object is to provide a method of knitting fabrics and garments from lengths of woven fabric.

Another general object is to provide a garment which combines the elastic characteristics of a knitted garment with the durability and strength and the dressy effect of a garment made from woven fabric.

Other objects and advantages inherent in the invention will become apparent from the accompanying detailed description taken in conjunction with the accompanying drawing in which:

Figure 1 is a view in perspective of a knitting machine on which the invention is carried out;

Figure 2 is an enlarged view of the ribbon carrier and guide on the machine;

Figure 3 is an enlarged view of the tensioning device for holding the ribbon taut during the knitting operation;

Figure 4 is a plan view of the needle beds on an enlarged scale of the machine shown in Figure 1;

Figure 5 is a diagrammatic view of the loops of two succeeding courses of knitting.

The inventive idea, which contemplates broadly the formation of a knitted fabric and garment from lengths of woven material, is adapted to a variety of expressions and the views shown in the drawing are for the purpose of illustration only and are submitted merely to facilitate the description of the invention as a whole and not to define the limitations thereof.

The main uses of knitted fabrics call for an elastic web. This elasticity is due to the capacity of each loop of yarn to change its shape in the direction of any strain upon it. This is easily ac-

complished when yarns are used which are substantially elastic in themselves. Woven fabric, on the other hand, is comparatively non-stretchable and loops formed therefrom, if knitted closely together, do not easily change their shape. However, in view of the fact that woven fabric is more durable and can withstand greater strain and wear, it has become desirable to knit fabrics and garments from woven material.

The basis of all knitted fabric is, of course, the loop and all fabrics made on a looped basis are considered as knit goods irrespective of the mode of the loop. Plain knit fabric is composed of a series of courses composed of loops, each course of which is intermeshed with the preceding and succeeding course. The real knitting operation, therefore, may be characterized as drawing a new loop through a previously formed one which then becomes the old one through which a new one is again drawn and so on.

In conventional knitting, the loops and courses are crowded and small, particularly if fine yarn is used. Woven fabric, such as ribbon, however, does not lend itself to such a method. The result would be a very stiff and boardy fabric. The invention has over-come this objection by spacing the loops as well as the courses and wales comparatively widely apart. In this manner, the stitches present the appearance rather of loosely tied knots which tighten when the fabric or garment is subjected to a strain but again loosen up when the tension is released.

A better understanding of the invention may be obtained by describing the method of operation performed on the machine illustrated by way of example in the drawing.

In this type of machine, the usual front and rear needle beds 10 and 11 carry the needles 13 which are controlled to form stitches through the medium of the locking mechanism supported by the carriage generally indicated by the reference character 14 (Figure 1). The machine is operated by reciprocating the carriage 14 over the needle beds 10 and 12. During the reciprocating movement, the carriage controls the needle jacks associated with the various needles to accomplish the regular knitting operation in the customary manner.

As shown in Figure 4, the needles 13 are spaced relatively widely apart except where the selvage of the fabric is to be formed. The reference character 13a indicates grooves in the needle bed in which the needles operate and the conventional knitting contemplates a needle in each of these grooves or in the grooves of at least one of the

beds. It will be noted from the drawing that in the invention the needles skip several grooves.

It will be understood, of course, that different kinds of loops and stitches may be used depending upon what design is to be produced. Whatever stitch is used, however, the same should be spaced widely apart and interconnected by a non-knitted length of material.

It has been found that a practical and strong web can be formed by having each needle in the front and rear beds form a loop. These loops are referred to as 15 in Figure 5 of the drawing. The needles in one of the beds are offset slightly from the needles in the other bed as shown in Figure 4.

16 This arrangement results in the formation of two adjacent loops 15a and 15b as shown in Figure 5. The relative position of these two loops are then reversed and these reversed loops are intermeshed or locked with the loop of the succeeding wale.

20 The reversing or shifting of the loops is accomplished by a conventional shifting mechanism including the links 16, 17 and 18 and the rack 19 and the handle 21.

This type of stitch or knot formation locks the loops securely without having to be pulled taut and makes possible an intermediate space of unstitched material of considerable length. This arrangement gives the stitches or knots a chance to contract or expand according to the strain imposed upon the web.

As previously indicated, the knitting machine proper is of a conventional construction and forms no part of the invention. It is important for the best results to present the ribbon 20 from which the fabric is made in a flat, untwisted condition. Since the yarns from which the conventional fabrics have been knitted heretofore have no width, there has been no need or demand for any particular guides for the yarns.

40 It has, therefore, been necessary to modify the machine to the extent of providing means for maintaining the ribbon in a flat, taut and un-

5 twisted condition. These means include the spool 21 which may be disposed horizontally on the frame of the machine as shown in Figure 1 of the drawing. A retard spring 22 may also be provided so that the ribbon 20 will unwind therefrom only under tension.

The ribbon, after leaving the spool 21, is engaged by the spring tensioning member 23 which is provided with a vertically narrow and horizontally elongated opening or eye 24 for smoothing out the flat ribbon. Similar openings or eyes are provided in the frame member 25 and in the yarn carrier 26.

As previously indicated the selvage of the fabric or the border of the garment is preferably formed of closely formed loops. The non-elastic, stiff and boardy effect of this closely knit portion may be alleviated by the insertion of an elastic material such as elastic filaments or ribbon. These may be sewed on the inside of the 20 border. This may be desirable along the bottom edge of the garment, around the neck and around the selvage.

It will be understood that the foregoing description has been made without limitation and various modifications may be resorted to within the scope of the following claims.

What is claimed is:

1. A knitted fabric web made from woven, non-elastic ribbons in which the stitches are spaced 30 apart and consist of relatively loose knots interconnected by lengths of unknitted ribbon whereby said knots will become tightened when the web is subjected to tension and will resume their original condition upon the release of the tension. 35

2. A knitted garment made from a web formed from lengths of non-elastic woven fabric, the stitches of said web being spaced apart and consisting of substantially loose knots interconnected by lengths of unknitted fabric.

HANS BOEPPELLE.
